UNITED STATES PATENT OFFICE

GEORGE F. VASEY, OF SCRANTON, PENNSYLVANIA, ASSIGNOR TO RIDGELY HEATER COMPANY, OF SCRANTON, PENNSYLVANIA, A CORPORATION OF NEW JERSEY

HEATER

Application filed May 18, 1927, Serial No. 192,260. Renewed October 3, 1930.

This invention relates to a coal burner adapted to be installed in various forms of furnaces and other heaters for effecting a more complete and perfect combustion of the fuel than has heretofore been practiced.

The main object is to provide a simple, practical and highly efficient fuel burner of this character capable of being easily and quickly installed in any heater and comprising what may be termed a triplex construction in that it involves the use of three essential grate elements assembled in such relation as to produce complete combustion and incineration of the smaller and least expensive grades as well as the various other grades of anthracite and other carboniferous fuels, resulting in a greatly reduced cost of operation of the heater; maximum intensity of heat from a given quantity of fuel, and minimum loss of combustible gases liberated from the combustion chamber to the draft flue.

In other words, I have sought to produce and to maintain a multi-stage conversion of the fuel into heat, first by distillation and distribution of the gases from and into the fuel, second, combining these gases with a sufficient quantity of fresh air to produce the desired combustible mixture, and third, to utilize the heat developed by distillation for the complete combustion of the mixture in the combustion chamber of the heater.

Another object is to construct and assemble the fuel-supporting sections of the burner in such manner as to cause the fuel to gravitate along downwardly converging surfaces thereof to a relatively narrow intervening passage at the bottom near the angle of convergence so that the downward feed of the fuel along said surfaces will be in opposition and thereby effect an automatic retention of the fuel against excessive discharge through the intervening space at the bottom thereby establishing what may be termed an angle of repose at or near the line of convergence of the inclined surfaces.

A further object is to place the horizontal grate in a plane below but adjacent the line of convergence of the inclined surfaces of the superposed grate sections and across the

intervening space to receive the ash as it is discharged through said space and to define the angles of repose.

Another object is to support the horizontal grate in such manner that it may be moved back and forth in its plane relatively to the superposed sections. 55

Another object is to provide a single support for the three grates without interfering with the free liberation of ashes to the underlying ash box, not shown. 60

Another object is to provide means for raising and lowering one of the fuel-supporting grates relatively to the other grate sections for agitating the fuel, when desired. 65

Another object is to provide means for supporting the burner at different heights relatively to the heater in which it is installed as may be required according to the height of the draft pipes leading from the combustion chamber to the main flue or chimney. 70

Other objects and uses of the burner will be brought out in the following description.

In the drawings:—

Figure 1 is a top plan of my improved coal burner as used in heaters having circular combustion chambers. 75

Figure 2 is a vertical sectional view of the same burner taken on line 2—2, Figure 1. 80

Figure 3 is a horizontal sectional view taken in the planes of line 3—3, Figure 2. 85

Figure 4 is a side elevation of the grate supporting frame or spider showing a portion of the lower horizontal grate and also the lower portion of the center grate. 85

Figure 5 is a side elevation, partly in section, of the lower horizontal grate and operating means therefor together with a portion of the supporting frame, and center grate, the dotted lines indicating the operating means for raising and lowering the center grate. 90

Figure 6 is a plan of the operating lever for the center grate.

Figure 7 is a diagrammatic view of the cross sectional portion of the lower horizontal grate and adjacent lower ends of the superposed grates, illustrating what is meant by the angle of repose of the body of fuel. 95

As illustrated, the burner comprises a sys- 100

tem of, in this instance, three grates —1—, —2— and —3— together with a suitable supporting frame —4—, the grates —1— and —2— being provided with opposed downwardly converging fuel-engaging surfaces 5 having their lower ends disposed in approximately the same horizontal plane and in horizontally spaced relation to form an intervening opening —5— for the discharge of 10 ashes therethrough while the horizontal grate —3— is disposed in a plane below the lower ends of the fuel-engaging surfaces of the grates —1— and —2— to extend across and beyond opposite walls of the opening 15 —5— for receiving the ashes discharged from said opening.

The angles of inclination of the fuel-engaging surfaces of the grates —1— and —2— have a more or less definite relation to 20 a horizontal plane and to each other in that the vertex —a— of the angle of convergence of the two surfaces falls below the opening —5— and between the lower ends of the grates —1— and —2— and upper surface of 25 the horizontal grate —3— so that the gravity feed of the fuel along both inclined surfaces of the grates —1— and —2— toward the vertex —a— will oppose each other and establish what may be termed an angle of 30 repose or angle of retention of the fuel whereby the feed of the fuel through the opening —5— is automatically checked or retarded.

This angular relation and relative disposition of the grates —1— and —2— to the horizontal grate —3— and also the relative width of the grate —3— and opening —5— together with the distance of the grate —3— from the lower ends of the grates —1— and 40 —2— are based upon the normal angle of repose or self-retention which a body of coal of pre-determined grade would assume when piled up from a base of definite width or area somewhat as illustrated in Figure 7.

45 The upwardly converging lines —b—, Figure 7, indicate the angles of inclination (about 45°) of a body of "buckwheat" coal normally at rest on the horizontal grate —3— from edge to edge thereof while the grates —1— and —2— terminate at the inclines —b— to check the downward flow 50 of the fuel outside of said lines or beyond the inner and outer edges of the grate —3—.

It, therefore, follows that the grate —3— 55 may be made of different widths and placed at different levels relatively to the grates —1— and —2— and that the grates —1— and —2— may also be placed at slightly different angles and at different positions 60 along the lines —b—.

It is found, however, that the grates —1— and —2— should be placed at about 70° and 30° respectively from a horizontal to give the best results for the smaller and cheaper 65 grades of coal.

The intervening space between the lower ends of the grates —1— and —2— together with their angles of inclination in automatically checking or retarding the escape of the fuel through the space —5— constitutes one of the important features of the invention in that it cooperates with other features of the grates —1— and —2— in establishing and maintaining three distinct stages of combustion of the fuel, viz: the distillation-stage 70 in the zone or area of the fuel directly over the surface of the grate —2— where the gases are distilled off or liberated from the fuel, the mixing stage in the zone or area of the fuel adjacent and extending inwardly from 75 the inner surface of the grate —1— where fresh air is mixed with the liberated gases; and the complete combustion stage in the zone or area immediately adjacent and above the surface of the fuel or combustion chamber of 80 the heater where the mixture of carbonous gases and air is burned resulting in a maximum intensity of heat sufficient to incinerate the entire mass of coal from the top and sides downwardly or in reverse order from the 85 distillation, mixing and combustion stages.

For the purpose of supporting combustion for the initial distillation of the fuel the grate —2— is provided with vertically spaced rows of apertures —6— extending there-through at different levels and communicating with the atmosphere through the underlying ash box, not shown, but commonly used in this type of heater.

The grate —1— is also provided with vertically spaced rows of openings —7— at different levels from bottom to top for admitting air which is by-passed from the exterior of the heater through the ash box and thence through the openings —7— to 105 mix with the distilled gases and to cause the mixture to be distributed through the fuel to effect complete combustion of the gases and also complete incineration of the coal.

In other words, the body of fuel within the 110 grate —1— and resting upon the grate —2— is first ignited at the surface of the grate —2— to which the air is admitted through the openings —6— to support combustion of the fuel immediately above the grate for distillation purposes.

Then as the gases are liberated and distributed through the superposed body of fuel the air is admitted through the openings —7— to mingle with the gases and thereby 120 to effect combustion of the latter by the same heat which produces the distillation or liberation of the gases.

This mixture permeates the entire mass of coal above the grate —2— and burns with 125 a maximum intensity at the surface and within the combustion chamber and also effects a complete incineration of the fuel solids.

This complete and rapid combustion of the gases reduces to a minimum the liability of 130

escape of any of the live gases from the heater while the complete incineration of the fuel together with the downwardly converging surfaces of the grates —1— and —2— enables the ashes to readily precipitate onto the underlying horizontal grate —3— which may be shaken at intervals when desired to discharge the ashes into the underlying ash pit, not shown.

10 The grates —1— and —2—, as illustrated, are frusto-conical and grate —3— is circular, but obviously the shape and size may be materially modified to conform to heaters of different shapes and sizes without departing from the spirit of this invention so long as the surfaces of the grates —1— and —2— converge downwardly to form an intervening space between their lower ends with the vertex of the angle in approximately vertical alignment with the opening or space and between the lower ends of the grates —1— and —2— and upper surface of the underlying ash grate —3—.

15 The main supporting frame —4— comprises, in this instance, a central hub —8— co-axial with the grates —1—, —2— and —3— and provided with a central vertical opening —9— for receiving a central downwardly extending stem —10— of the grate —2—, the upper portion of which is enlarged to form a shoulder —11— adapted to normally rest upon the upper end of the hub —8— for holding the grate —2— against undue downward movement while permitting its free vertical movement.

20 The vertical opening —9— in the hub —8— and also the stem —10— of the grate —2— are angular or substantially square in cross section to hold the grate —2— against angular movement relatively to the hub —8—.

25 The hub —8— is provided with a plurality of, in this instance four, outwardly projecting flanges —12— arranged in uniformly spaced relation circumferentially as shown in Figure 3 for operative connection with a corresponding number of supporting arms —13— which also serve as a means for supporting the grate —1— in a manner presently described.

30 The inner ends of the arms —13— are provided with recesses —14— in corresponding upright faces thereof for receiving the corresponding flanges —12— of the hub —8— and thereby supporting said hub against relative vertical movement, the recesses being open at corresponding sides or faces to permit the flanges —12— to readily enter the same by relative angular movement of the hub relatively to the arms, or, by a reverse angular movement the flange —12— may be disengaged from their respective recesses —14—.

35 When the flanges —12— of the hub —8— are properly seated in their respective recesses —14— they are clamped to the back

walls of said recesses by bolts —15— as shown more clearly in Figures 3 and 4.

40 The recesses —14— are preferably formed on corresponding sides of upstanding lugs —16— on the inner ends of the arms —13— to afford lower, upper and back walls against which the flanges —12— may rest when the hub —4— is placed in operative position upon the inner ends of the arms.

45 The outer ends of the arms —13— are provided with upstanding flanges —17— having vertical openings —18— for receiving lugs on the lower ends of the grate —1— as shown in Figure 2.

50 The grate —1— is preferably composed of a plurality of, in this instance four, similar sections arranged edge to edge circumferentially and having their lower ends resting upon the upper edges of the flanges —17—, the lower ends of the meeting edges of said sections being provided with the downwardly extending lugs —19— which are seated in the apertures —18— to hold the grate against circumferential movement relatively to its supporting arms —13—.

55 The object in making the arms —13— separate from the hub —8— is to permit the use of arms of different lengths for furnaces of different sizes with the same hub thereby avoiding the necessity of replacing the entire frame in changing from one size heater to another.

60 The frame —4— is adapted to be supported upon or within the ash box commonly used in heaters of this character and in order that the same frame may be used for heaters of different sizes the arms —13— are provided with adjacent extensions —19'— secured to the underside thereof by bolts —20—, Figure 2, and provided with lengthwise slots —21— as shown in the lower left hand of Figure 2 for receiving said bolts and permitting the extensions —19'— to be adjusted laterally and, if necessary, circumferentially with reference to the bolts —20— as may be necessary for attachment of said extensions to existing supports upon the ash box.

65 In the use of coal burners of this type it is desirable to support it in such manner that it may be adjusted vertically for the purpose of lengthening or shortening the fire travel of the gases as may be necessary in the use of the burner in different heaters in which the height of the draft flue varies.

70 For example, if the burner is too close to the stack and the fire travel through the intervening space is too short to permit the gases to give off their heat the live heated gases will be carried into the stack at a relatively high temperature and consequent loss of heat for distribution through the heat distributing chamber of the heater, or, where the distance of fire travel between the combustion chamber and the exit of the combustor

tion chamber and burner is too great the draft would be somewhat unduly retarded to such an extent as to reduce complete combustion of the gases resulting in obstructing the free flow of the products of combustion through the draft flue or chimney.

In order to overcome these objectionable results in the simplest possible manner the outer ends of the arms —19— are provided with vertical apertures —22— for receiving vertically adjustable supporting legs —23— which are held in their adjusted positions by set screws —24— and are provided with offset feet or hangers —25— adapted to rest upon such supports of the ash box as may be available, said legs being reversible as shown by dotted lines in Figure 2 in addition to their vertical adjustability to permit the frame to be supported on the ash box either from above or below the extensions —19—.

The upper surfaces of the arms —13— between the lugs —16— and flanges —17— are substantially flat and horizontal for receiving and supporting the horizontal grate —3— which is provided with annular ribs —3'— concentric with the axis of the hub —8— and extending entirely around the outer end edges of the lugs —16—, the lower edges of the ribs —3'— being rounded in cross section so as to reduce their area of contact with the underlying portions of the arms —13—.

The grate —3— is oscillatory about its axis for removing the ashes therefrom and for this purpose the grate —3— is preferably divided diametrically in opposite half sections having their meeting edges spaced a sufficient distance apart to receive between them the reduced upper ends of a pair of downwardly projecting studs —26—.

A shaker rod —27— is adapted to be connected at one end to the lower ends of either one of the studs —26— where it is held in operative position by a cotter key —28—, the outer end of the shaker rod being extended to the front of the heater and is provided with a handle —29— by which it may be operated back and forth at will for effecting the angular movement of the grate —3—.

The stem —10— of the center grate —2— extends above and below the upper and lower ends of the hub —8— and is preferably hollow the major portion of its length and provided near its lower end with air inlets —30— communicating with the atmosphere preferably through the ash box, said stem being provided near its upper end with an air outlet —31— above the adjacent end of the hub —8— to allow air entering the stem to pass outwardly beneath and through the apertured portions of the grate —2—.

The extreme lower end of the stem —10— is provided with an apertured lug —32— for receiving one end of a lever —33— having a pivotal pin —34— adapted to engage in a bracket —35— on one side of the hub —8—

between two of the lugs —16— as shown in Figures 4 and 5, said lever being extended forwardly from its pivot —34— to the front of the heater where it is accessible for operation at will for raising the center grate —2— from its normal position as, for example, when it is necessary to break up any slag or clinker which may accumulate on the surface of the grate and also to temporarily vary the vertex of the downwardly converging angles of the upper fuel-supporting surfaces of the grates —1— and —2—.

Operation

When installing the burner in a heater the legs —23— with the extensions —19— thereon will first be placed in or upon the ash box of the heater either in the position shown by full lines in Figure 2 or in the position shown by dotted lines in the same figure after which the arms —19— will be adjusted to the same level along the legs —23— according to the height at which it is desired to support the burner relatively to the combustion chamber and to the outlet for the products of combustion.

Following this operation the arms —13— will be placed in operative position upon the extensions —19— in uniformly spaced relation to the axis of the burner whereupon the hub —8— will be placed in operative position with its flanges —12— in their respective recesses —14—, the bolts —20— and —15— being then tightened to firmly hold the arms —13— and hub —8— in their operative positions.

The grate —3— may then be placed in operative position upon the upper flat surfaces of the arms —13— and connected to its operating lever —27— in the manner described.

The grates —1— and —2— may then be placed in operative position upon the flanges —17— and within the hub —8— respectively and the lower end of the stem of the grate —2— connected to its operating lever —33— in the manner described, thus completing the burner ready for receiving fuel, it being understood that the sections of the grate —1— will be placed in operative position one at a time and that their upper edges will lie in close proximity to the inner walls of the heater chamber in which the burner is installed.

The basket grate —1— extends from approximately the horizontal plane of the lower edge of the inner grate —2— some distance above the upper end of the inner grate for confining the fuel upon and around said inner grate.

The basket grate is then filled with coal from the upper surface of the inner grate to the top of or above the outer grate —1— with the result that the gravity feed of the fuel along the downwardly converging surfaces of the grates —1— and —2—, is in op-

position, particularly at the outlet or opening —5— or at the vertex —a— of convergence resulting in the self-retention of the fuel against discharge through the outlet onto the underlying grate —3—, the angle of convergence being termed the angle of retention at the opening —5—.

The lower strata of the fuel adjacent the upper surface of the inner grate —2— may be ignited in any well-known manner supported by the introduction of air through the openings in the grate —2— and by reason of the superposed mass of unburned fuel re-

it may be conveniently removed by slight shaking of the grate about its axis.

This successive distillation, distribution and combustion of the gases and incineration of the fuel in the manner described are highly important factors in the economic burning of the smaller grades as well as various other grades of coal either anthracite, or bituminous and when considered in connection with the provision of means for adjusting the burner to different heights as may prove most efficient according to different levels of the outlet of the combustion chamber, 75

frame having upstanding apertured flanges, an upwardly flaring basket grate having its lower end provided with lugs seated in the apertures in said flanges, and a horizontal grate supported upon the frame in a plane below the lower end of the basket grate in spaced relation thereto, said horizontal grate being adjustable angularly relatively to the basket grate and an upwardly tapered grate supported on the frame within the lower end of the basket grate.

7. A coal burner comprising a grate-supporting frame, an upwardly flaring basket grate having its lower end supported on said frame, a center grate mounted on the frame and provided with an upwardly tapering fuel supporting surface of less diameter than the interior diameter of the lower end of the basket grate to form an intervening marginal space, and a horizontal grate supported upon the frame in a plane below the lower ends of the basket grate and the center grate to extend across the intervening space between the basket grate and center grate and having its upper face in a plane below the vertex of convergence of the surfaces of the basket grate and center grate.

8. A coal burner comprising a grate supporting frame, an upwardly flaring basket grate having its lower end supported on said frame, a center grate mounted on the frame and provided with an upwardly tapering fuel-supporting surface of less diameter than the interior diameter of the lower end of the basket grate to form an intervening space, and a horizontal grate supported upon the frame in a plane below the lower ends of the basket grate and the center grate to extend across the intervening space between the basket grate and center grate, and means for supporting the frame at different levels.

9. A coal burner comprising a grate-supporting frame, an upwardly flaring basket grate having its lower end supported on said frame, a center grate mounted on the frame and provided with an upwardly tapering fuel-supporting surface of less diameter than the interior diameter of the lower end of the basket grate to form an intervening space, and a horizontal grate supported upon the frame in a plane below the lower ends of the basket grate and the center grate to extend across the intervening space between the basket grate and center grate, said frame being provided with laterally extensible supporting arms to conform to heaters of different sizes.

10. In a coal-burner, co-axial circular grates having opposed downwardly converging fuel engaging surfaces in spaced relation at the bottom, and a fuel-retention grate underlying the vertex of convergence of said surfaces and extending across said space, and means for oscillating the fuel-retention grate about the axis of the first named grate.

11. A coal-burner comprising a horizontal grate adjustable about a vertical axis, and additional upwardly extending grates arranged in horizontally spaced relation above the horizontal grate and having their lower ends terminating in planes above the horizontal grate and their adjacent sides converging downwardly so that the vertex of convergence falls within the space above the opposite edges of said horizontal grate.

In witness whereof I have hereunto set my hand this 7th day of May, 1927.

GEORGE F. VASEY.
